COMBINED CAMERA STAND AND PHOTOGRAPHIC LAMP HOLDER

Nalbro Frazier, New York, N. Y.

Application October 20, 1949, Serial No. 5,605

Term of patent 14 years

(Cl. D61—1)

To all whom it may concern:

Be it known that I, Nalbro Frazier, a citizen of the United States residing at city of New York, county of New York, and State of New York, have invented a new, original, and ornamental Design for a Combined Camera Stand and Photographic Lamp Holder, of which the following is a specification, reference being had to the accompanying drawing, forming part thereof.

Fig. 1 is a perspective view of the side of a combined camera stand and photographic lamp holder embodying my design.

Fig. 2 is a perspective view of the front thereof.

Fig. 3 is an enlarged fragmentary perspective view of the front of the top portions thereof.

Fig. 4 is a fragmentary perspective view of the side and front of the top portions thereof.

I claim:

The ornamental design for a combined camera stand and photographic lamp holder, substantially as shown.

NALBRO FRAZIER.
